(57) **CLAIM**

The new design for the accessory stand, as shown and described.

DESCRIPTION

FIG. 1 is a top, front and left perspective view of an accessory stand in open state showing our new design;

FIG. 2 is a front view thereof;

FIG. 3 is a rear view thereof;

FIG. 4 is a right side view thereof;

FIG. 5 is a left side view thereof;

FIG. 6 is a top side plan view thereof;

FIG. 7 is a bottom side plan view thereof;

FIG. 8 is a top, front, and left perspective view of the accessory stand of FIG. 1 in close state;

FIG. 9 is a top, rear, and left perspective view of the accessory stand of FIG. 1 in open state;

FIG. 10 is a perspective view of FIG. 8 with a pad shown in broken lines for convenience of illustration and forming no part of the claimed design; and,

FIG. 11 is a perspective view of FIG. 9 with a pad shown in broken lines for convenience of illustration and forming no part of the claimed design.
